UNITED STATES PATENT OFFICE.

WILBER S. SALISBURY AND WILLIAM ARMSTRONG, OF CHICAGO, ILLINOIS.

POR TABLE BOAT.

SPECIFICATION forming part of Letters Patent No. 243,084, dated June 21, 1881.

Application filed January 28, 1881. (No model.)

To all whom it may concern:

Be it known that we, WILBER S. SALISBURY and WILLIAM ARMSTRONG, of Chicago, Illinois, have invented a new and useful Portable 55 Collapsing Boat, of which the following is a specification.

Our invention relates to improvements in portable collapsing boats in which vertical adjustable stem-timbers and horizontal gunwale 10 and bilge timbers with removable seats, arranged with extension-legs and removable sectional keel-boards, operate in conjunction with a flexible skin or cloth covering; and the objects of our improvements are, first, to provide 15 adjustable stems; second, to afford facilities for the proper adjustment of the seat-legs independent of each other in respect to the keel-boards; third, to make longitudinal timbers in sections, to more readily facilitate the collapsing and carrying; and, fourth, to provide 20 a skin or covering of flexible material, so arranged as to be readily attached or removed from the timbers. We attain these objects by the mechanism illustrated in the accompanying 25 drawings, in which—

Figure 1 is a top view of the boat as it appears set up, and with sections of the seats removed to show the plan of fastening the keel-boards. Fig. 2 is a vertical sectional view of 30 the boat from end to end. Fig. 3 is a vertical cross-section amidships. Fig. 4 is a vertical end section enlarged. Fig. 5 is a section showing the manner of lacing the skin to the gunwales. Fig. 6 is a vertical section of the end 35 seats. Fig. 7 shows detail views of the hinged extension-legs.

Similar letters refer to similar parts throughout the several views.

A A A are the gunwale-timbers, made in 40 sections. B B B are the bilge-timbers, made in sections. C C C are ferrules upon the gunwale and bilge timbers. D D are stationary stems, to which the gunwale and bilge timbers are secured by means of an iron-bar 45 connection. E E are movable stem-posts, and are provided with nuts and screw-bolts, F F F. f f are loose nuts on the screw-bolts. F F F are screw-bolts passing through stem-timbers D D. G G G are hook-clasps attached to 50 the gunwale-timbers; H H H H, chains and hooks attached to the seats; I I I I, brace-

timbers, provided with notches for the ends of the seat to slip into. J J J are the seats and shapers for the gunwale and bilge timbers. K K K are the seat-legs hinged to the under 55 side of the seat, and provided with extension-pieces with numerous holes and bolts with nuts; L L L, extension-pieces attached to seat-leg; M M M M, gunwale-lacing for attaching the skin to timbers; N N N N, keel-boards in 60 sections connecting under each seat; O O O, batten-strips on keel-boards. P P P and R R R are bars and sockets for connecting keel-boards; S S S, bolts for extension-piece on legs; T T, leather strap and buckle to prevent 65 leg from tripping; U U, brace-clips. (See Fig. 3.) V V V V are staples, ferrule, and eyebolt for connecting gunwale and bilge timbers to stem-timbers; W W, stem-rope fastening, made fast to skin and eyebolt X; Y Y, nuts for receiving end of screw-bolt; Z Z, skin or covering, without seam in bottom; a', batten-blocks on end of keel-board, and b' amidships.

To set the boat up, we first connect the gunwale and bilge timbers (which are numbered) with the ferrules. The frame is then placed in the skin. Then fasten the rope on each end of the skin to the eyebolt in stems E E. Next proceed to lace the loops attached to skin by passing each loop over the gunwale 75 timbers, then through the eyelet, and proceed to lace one loop into the other from end to end, as shown in Fig. 6, and fasten the last loop with a half-hitch. The small seats J J are pushed into the notch in the brace-timbers, 80 and the chains on the seats are hooked into the clasps on the gunwale, which lock them fast. The keel-boards are then put into position and held there by pushing the bars into the sockets R R. Then the hinged legs are 85 forced down upon the keel-boards. Then buckle the strap which keeps the leg from tripping. (The keel-boards are so arranged that the joints of each section of the same come under the center of each leg of the seats.) The center 90 seat is put in last and locked with the chains to the gunwale-clasps, the hinged legs forced down to blocks b' b'. The strap is then buckled, thus completing the setting up of the boat.

To make up into a sectional package, un-buckle the straps first. Then close the legs and unhook the chains. Take out the middle seat 100

first. Now remove the keel-boards and then the small seats. Then proceed to undo the lacing and unhitch the rope from eyebolt at the stems. Then remove the frame from the skin. The timbers can now be unferruled and the frame made into a package.

To collapse the boat into a full-length package, remove the keel-boards and seat-spreaders, as previously set forth. The sides then come together, making a flat package the full length of boat, in which can be stored the seats and keel-boards edgewise, making a convenient package for portage, storage, and shipment.

15 An important feature, should the skin become slack through use, is to tighten it longitudinally by the screws at each end and vertically by the means of the extension-legs, letting out one or more holes, as required, thus 20 always keeping the skin smooth and taut.

What we claim as our invention, and desire to secure by Letters Patent, is—

1. The combination, in portable boats, of sectional gunwale and bilge timbers, connected

by braces I I and fastened to stem-timbers D 25 D, operating in conjunction with the movable stems E E and spreaders J J J, keel-boards N N, and skin Z Z, all substantially as set forth.

2. In a portable boat having a flexible skin, the movable stem-posts E E, provided with screw-bolts F F F F, passing through stationary stems D D, for the purpose of longitudinal adjustment of the flexible skin, in combination with the spreaders H H and extensible hinged legs K K, affording crosswise adjustment, all substantially as set forth and described.

3. In portable boats, the combination of seats J J J, as shapers and spreaders, provided with chains and hooks H H, hinged extension-legs 40 K K K, and buckle-straps T T, all substantially as set forth.

WILBER S. SALISBURY.

WILLIAM ARMSTRONG.
